(57) CLAIM

The ornamental design for footwear, as shown and described.

DESCRIPTION

FIG. 1 is a top perspective view of footwear;
FIG. 2 is a bottom perspective view thereof;

FIG. 3 is a front view thereof;

FIG. 4 is a back view thereof;

FIG. 5 is an outer side view thereof;

FIG. 6 is an inner side view thereof;

FIG. 7 is a top view thereof; and,

FIG. 8 is a bottom view thereof.

The elements shown in FIGS. 1–8 that are overlaid with a white transparent mask bounded by broken lines represent portions that form no part of the claimed design.

1 Claim, 8 Drawing Sheets
